UNITED STATES PATENT OFFICE.

OTTO LAUBER, OF ESSEN-ON-THE-RUHR, GERMANY, ASSIGNOR TO FRIED. KRUPP AKTIENGESELLSCHAFT, OF ESSEN-ON-THE-RUHR, GERMANY.

PORATABLE GUN.

No. 923,052.

Specification of Letters Patent.

Patented May 25, 1909.

Application filed July 23, 1908. Serial No. 445,053.

To all whom it may concern:

Be it known that I, OTTO LAUBER, a subject of the Emperor of Germany, and a resident of Essen-on-the-Ruhr, Germany, have 5 invented certain new and useful Improvements in Portable Guns, of which the following is a specification.

The present invention relates to portable guns, and the object of the invention is to 10 improve this type of guns in such a manner that the gun has sufficient stability on firing, even in case considerable lateral adjustment is imparted to the gun-barrel.

The object of the invention is attained by 15 providing auxiliary spade-members or stays provided with spades, the spade-members or stays being jointed to the mount in such a manner that they can be swung out laterally to resist reaction of firing when the gun-barrel has been adjusted laterally to a considerable extent.

One embodiment of the invention is shown in the accompanying drawings, by way of example.

25 Figure 1 is a side view of those parts of a gun to which the invention relates, some parts being broken away, and Fig. 2 is the corresponding top view.

The gun barrel B is mounted to slide on 30 the slide-track carrier A which, through the medium of the horizontal trunnions a^1 , is swingingly mounted in the cradle C. Through the medium of an elevating mechanism the cradle C is connected with the slide-track carrier A and, through the medium of a horizontal training mechanism, the cradle 35 can be swung relatively to the mount F about the axis of the vertical trunnion c^1 journaled in the mount F. The elevating mechanism and the horizontal training mechanism, which are not shown in the drawings, may be of any suitable construction. However, attention is drawn to the fact that the lateral training mechanism and the connection between the cradle and the mount permit of considerable lateral swinging movement of the gun-barrel (see the positions of the gun-barrel indicated in dotted lines in Fig. 2).

The mount is provided with wheels Q and 50 has a trail provided with a spade f^1 .

Two stays O, each of which is provided with a spade o^1 , are jointed to the side-walls of the mount near the bearing for the trunnion c^1 . By means of links P, which have one end 55 jointed to the side-walls of the mount and have their other end jointed to slides o^2 on the stays, the stays O can be swung about vertical bolts N which are mounted in bearings f^2 on the walls of the mount. In the 60 position of travel the stays O almost lie against the side-walls of the mount F as shown in dotted lines in Fig. 2. In the firing position the stays assume the position shown in full lines in Fig. 2. Through the medium 65 of bolts o^3 the slides o^2 can be rigidly secured to the stays in the positions which correspond to the extreme inner and outer positions of the stays O.

A view of Fig. 2 will demonstrate that, 70 when considerable lateral swinging movement is imparted to the gun-barrel, one of the stays O will always absorb the shock on firing. In this manner a tilting of the gun is in any case prevented with absolute certainty.

Without departing from the principle of the invention the trail proper might be composed of two parts jointed together in such a manner that the two parts could be spread 80 apart or folded together in a manner similar to the stays O.

Having thus described the invention, what is claimed and desired to be secured by Letters Patent is:

1. In a portable gun, the combination with the mount and the gun pivotally mounted thereon; of a spade member jointed to the mount and capable of being swung laterally to the mount to a position opposite to the direction in which the gun may be pointed.
2. In a portable gun, the combination with the mount, of a pair of spade members jointed to the mount and capable of being spread apart in the rear of the mount to resist forces 95 at angles to the mount.
3. In a portable gun, the combination with the mount and its trail provided with a

spade, of an auxiliary spade member jointed to the mount and capable and adapted to support said mount rearwardly and laterally.

4. In a portable gun, the combination with
5 the mount, of a pair of spade members jointed to the mount and adapted to support said mount rearwardly and laterally.

The foregoing specification signed at Düsseldorf, Germany, this 22nd day of June, 1908.

OTTO LAUBER.

In presence of—

PETER LIEBER,
WILHELM FLASCHE.
